(57) **CLAIM**

The ornamental design for a cap for a pharmaceutical container, as shown and described.

DESCRIPTION

FIG. 1 is a perspective view showing a representative embodiment of a cap for a pharmaceutical container of our new design in its intended environment as indicated by broken lines;

FIG. 2 is a left side elevational view thereof, the right side elevational view being identical thereto;

FIG. 3 is a front elevational view thereof, the rear elevational view being identical thereto; and,

FIG. 4 is a top plan view thereof, the bottom plan view being plain and unornamented.

It is noted that the broken lines of FIG. 1 are for illustrative purposes only, and form no part of the claimed invention.
